(57) **CLAIM**

We claim the ornamental design for a fluid dispenser, as shown and described.

DESCRIPTION

FIG. 1 is an upper left perspective view of a fluid dispense showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged perspective view of the underside of the lip of the liquid dispenser showing the outlet enlarged thereof.

The broken lines in the figures are for contextual purposes or show the environment and form no part of the claimed design.

The dot-dash line adjacent unshaded areas represent bounds of the claimed design and form no part of the claimed design themselves.
